SNAP FASTENER TAPE

Leo Roseman, Newark, N. J.

Application March 14, 1933, Serial No. 660,626

5 Claims. (Cl. 2—265)

This invention relates in general to fastener tape including a strip of fabric having separable fastener elements attached thereto, to be applied to the edges of openings in garments for fastening such edges together. More particularly the invention is directed to such fastener tape embodying so-called snap fasteners or head and socket fasteners.

Snap fastener tape is known in the art, as shown by my Patent No. 1,373,452 dated April 5, 1921, and others, but the manufacture has not been as economical as desired because of the difficulties encountered in sewing the snap fastener elements on the fabric strips, and particularly in sewing the snap fastener elements on the fabric strips adequately secure to prevent the fasteners from being pulled off or separated from the strips under the strains incident to the use of the tape.

In the tape shown in my said patent, several lines of stitching are required for attaching the fastener elements to the fabric strips, and the stitching is so spaced from the fastener elements that said elements are not so securely held on the tape as is desirable where the tape is subjected to severe strains; and generally several operations are required for making the plural rows of stitches. The manufacture of the tape is therefore quite expensive.

One object of my present invention is to provide snap fastener tape of the general character described wherein all of the fastener elements shall be sewed on the tape with one continuous line of stiches without jump stitches or interrupted stitches and without the necessity for cutting threads between the fastener elements, and said line of stitches shall also serve to secure the piles of the fabric strip together along their longitudinal edges, whereby the tape can be rapidly sewed on automatic machines and shall be inexpensive, the stitches shall be prevented from unraveling or pulling out around the fastener elements and the fasteners shall be securely attached to the fabric strip.

Another object is to provide snap fastener tape of this character wherein all fastener elements on the same strip of fabric shall be secured on the strip by a single continuous line of stitches which shall connect together the fabric piles between which the fasteners are located and shall comprise portions one completely encircling or surrounding each fastener element at its perimeter, and other portions each extending longitudinally of the strip between two adjacent fastener elements, whereby the fastener elements can be se-

curely sewed on the strip in one continuous operation on an automatic machine, and stitches shall be uninterrupted or unbroken from one end of the strip to the other so that unraveling or pulling out of the stitches shall be practically impossible. 5

Other objects are to provide fastener tape of the character described wherein the junction of the fastener encircling portions and the longitudinal portions of said line of stitches shall be made by lateral stitches disposed radially of the fastener elements to facilitate the sewing operation and so that the longitudinal portions of said continuous line of stitches shall be spaced from the fastener elements and said portions can be 10 covered and concealed on the face side of the tape by the edge of a garment without a flap or fly when the tape is secured to the latter, whereby a minimum number of lines of stitches shall 15 be visible on the face side of the garment to ensure a neat appearance, and without the use of a flap or fly; and to obtain other advantages and results as will be brought out by the following 20 description.

Referring to the accompanying drawing in 25 which corresponding and like parts are designated by the same reference characters throughout the several views,

Figure 1 is a fragmentary plan view of cooperating strips of head and socket fastener tape 30 showing the same applied to the edges of a garment opening and viewing the same from the face side thereof.

Figure 2 is an enlarged fragmentary plan view 35 of one of the strips which carries the socket fastener elements.

Figure 3 is an enlarged isometric sectional view through the tape carrying the socket fastener elements,

Figure 4 is a similar view of the tape having 40 the head fastener elements and

Figure 5 is a fragmentary plan view similar to Figure 2, showing a modification of the invention.

Specifically describing the illustrated embodiment of the invention, the reference character A designates the tape which carries the socket fastener elements, and B designates the tape which carries the head fastener elements to cooperate with the socket fastener elements of the 50 tape A.

The tape A is shown as formed of a strip of fabric comprising a single piece which is folded into a plurality of plies 1, 2 and 3. The plies 2 and 3 are of substantially the same width, while 55

the ply 1 is materially wider than the two plies 2 and 3. As shown, the plies are formed by longitudinally folding the strip of fabric at 4 to form a ply 3 and then again folding the fabric at 5 to 5 form a ply 2 which is interposed between the plies 1 and 3. Obviously, instead of forming the strip of one piece of material, the strip may comprise separate pieces of fabric arranged in superposed relation.

10 A plurality of socket fastener elements 6 of known construction are arranged in a row in spaced relation longitudinally of the tape between the two adjacent plies 1 and 2 with the opening 7 of each element facing toward the ply 2. The 15 plies 2 and 3 are formed with registering openings 8 which also register with the opening 7 of the socket member to permit the head of a cooperating head fastener element to enter the socket member. As shown, the socket member 20 6 is approximately circular in plan view and has the usual spring 9, portions of which project into the socket through slots 10 to engage the head 11 of a cooperating head fastener element 12.

The socket fastener elements 6 are securely 25 attached to the fabric strip by means of a single continuous line of stitches passing through the plies 1, 2 and 3 and including portions 13 one surrounding each socket fastener element 6 at its perimeter, and other portions 14 each running 30 longitudinally of the strip between two adjacent fastener elements. Preferably the longitudinal portions 14 are offset or spaced from the row of fastener elements and are connected with the portions 13 by stitches 15 which extend laterally 35 of the strip. As shown, the longitudinal portions 14, the lateral stitches 15 and the portions 13 form parts of one continuous line of stitches, and each lateral stitch 15 connects one end of one of the portions 13 with one end of an adjacent 40 longitudinal portion 14. Also, preferably, the lateral stitches 15 are radially disposed with respect to the fastener elements 6 and at right angles to the longitudinal portions 14.

With this construction, the fastener elements 45 can be sewed upon the fabric strip with a single continuous line of stitches and in one continuous operation so that the tape can be sewed on automatic machines, can be rapidly produced and is relatively inexpensive.

50 Furthermore, the portions 13 encircling the fastener elements securely hold the fastener elements against movement on the tape, and the two plies 2 and 3 overlying the face side of the socket elements effectually reinforce the tape 55 against the strains incident to pulls upon the socket elements in separating them from the head elements 12. The lateral stitches 15 facilitate the formation of the longitudinal portions and fastener encircling portions 13 in one continuous line, and also by the use of these lateral stitches the longitudinal portions can be spaced from the fastener elements so that said longitudinal portions may be covered by the edge portion C of a garment to which the tape is applied 60 as shown in Figure 1 of the drawing, whereby a minimum number of lines of stitches will be visible on the face side of the garment. The stitches being in one continuous line, the possibility of the stitches being pulled out or unraveled around the fastener elements is extremely remote, and by forming the fastener encircling portions 13 in a continuous line with the longitudinal portions 14, the necessity for making jump stitches, or for loose threads between two 70 adjacent fastener elements is eliminated. The

lateral stitches 15 being angularly disposed with respect to the stitches 13 and 14 restrain unraveling of the stitches 13 and 14 especially at points adjacent the fastener elements, and reinforce the attachment of the fastener elements to the tape 5 at the ends of the fastener encircling stitches 13.

The tape may be applied to the edge portion C of a garment in the usual manner, the edge of the garment being laid over the free edge of the 10 plies 2 and 3 so that said edge portion overlies said longitudinal portions 14 and is in close relation to the fastener elements 6, as shown in Figures 1 and 3. Lines of stitches D and E may then be run through the edge portion of the garment and the tape longitudinally thereof for securing the tape to the garment. 15

The complementary strip B of fastener tape which carries the head fastener elements 12, is in general similar to the tape A. The tape B is also 20 formed of three plies of fabric 16, 17 and 18, and the head fastener elements 12 are arranged in a row in spaced relation longitudinally of the strip between the base ply 16 and the intermediate ply 17. The plies 17 and 18 are formed with registering openings 19 through which the head 11 of the fastener element projects. The head elements 12 are attached to the tape by a single continuous line of stitches identical with the line of stitches described in connection with the tape A. As shown on the drawing this line of stitches includes the portions 19 which encircle the fastener elements, the portions 20 which extend longitudinally of the strip between adjacent fastener elements, and the lateral stitches 21 which 30 connect the longitudinal portions with the fastener encircling portions. The tape B may be applied to the edge portion F of a garment in the usual manner by lines of stitches G. 35

The fastener elements 6 and 12 of the two 40 tapes cooperate in the usual manner of head and socket or snap fasteners, for example as shown in my above-mentioned Patent No. 1,373,452, the elements being connected by forcing the heads 45 11 of the head members into the sockets of the socket members, and the two fastener elements being held together by the springs 9 which frictionally engage the heads 11. Fastener elements are separated by pulling the tapes apart so as to withdraw the heads 11 from the sockets. During 50 this separating of the fastener tapes considerable strain is applied to the fastener elements both laterally and axially thereof. However, these strains are effectually resisted by the portions 13 and 19 of the line of stitches which encircle 55 the fastener elements at the perimeters of the elements and securely hold the elements against both lateral and axial movement on the tapes. The strains are further resisted by the two plies of fabric which overlie the face sides of the 60 fastener elements, and the lateral stitches 15 and the longitudinal portions 14 of the line of stitches further reinforce the attachment of the fastener elements to the tapes. 65

To provide additional security in the attachment of the fastener elements to the tapes the stitches of the fastener encircling portions 13 and 19 may be doubled, or in other words, a plurality of rows of stitches 22 and 23 may be formed around the fastener elements as shown in Figure 5. 70

While I have shown the fastener elements as circular in plan view it should be understood that the invention can be used in connection with fastener elements of other configurations, 75

and furthermore, while I have shown the fastener elements as of a certain form, it is within the scope of the invention to use other types of fastener elements. Therefore, I do not desire to be understood as limiting myself in the details of construction and use of the invention, except as required by the following claims when construed in the light of the prior art.

Having thus described my invention, what I claim is:

1. Snap fastener tape comprising a strip of fabric having a plurality of plies, snap fastener elements arranged between two adjacent plies in spaced relation in a row longitudinally of the tape, and a single continuous line of stitches passing through said two plies and including portions each running between two adjacent fastener elements longitudinally of said strip in spaced relation to one side of said row of fastener elements, other portions, one encircling each fastener element at its perimeter with the ends of said portion in close relation to each other, and lateral portions connecting the ends of said longitudinal portions of said line of stitches with the adjacent portions which encircle said fastener elements. 10
2. Snap fastener tape comprising a strip of fabric having a plurality of plies, snap fastener elements arranged between two adjacent plies in spaced relation in a row longitudinally of the tape, and a single continuous line of stitches passing through said two plies and including portions each running between two adjacent fastener elements longitudinally of said strip in spaced relation to one side of said row of fastener elements, other portions, one encircling each fastener element at its perimeter with the ends of said portion in close relation to each other, and lateral portions connecting the ends of said longitudinal portions of said line of stitches with the adjacent portions which encircle said fastener elements. 15
3. Snap fastener tape comprising a strip of fabric having a plurality of plies, snap fastener elements arranged in a row between two adjacent plies in spaced relation longitudinally of said strip, a line of stitches running through said two plies longitudinally of said strip in spaced relation to one side of said row of fastener elements, a line of stitches passing through said two plies and encircling each fastener element with the ends of said line in close relation to each other, and lateral stitches passing through said two plies at right angles to said longitudinal line and in radial relation to said fastener elements and connecting said longitudinal line of stitches to said ends of said lines of stitches encircling said fastener elements. 20
4. The snap fastener tape set forth in claim 1 wherein said lateral stitches extend at right angles to said longitudinal portions and in radial relation to said fastener elements. 25
5. A fastener strip comprising a strip of fabric having a plurality of plies, snap fastener elements arranged between two adjacent plies in spaced relation in a row longitudinally of the tape, and a single continuous line of stitches passing through said two plies and including portions one encircling each fastener element at its perimeter with the ends of said portion in close relation to each other, and other portions each running longitudinally of the strip between two adjacent fastener elements and offset at one side of said row of fastener elements, and lateral stitches connecting said longitudinal portions and said portions which surround said fastener elements. 30
